ioned type, however, it is necessary to tighten each one separately by means of the quoin key and to go around the form several times tightening them gradually, in order not to displace 5 the body of type or to distort the form. For example, assuming that each pair of quoins must be tightened four times to complete the operation, there would be 28 steps involved, since seven pairs of quoins are shown 10 in Fig. 1. By my invention, the entire operation would be completed by not more than eight steps and possibly less.

As will be seen in the drawings, each of my quoins 5 is wedge shaped and is provided 15 with the longitudinal rib 6 and the longitudinal groove 7 in the thicker end. In the sloping face of each quoin, there is also formed on either side of the longitudinal rib, the teeth 8 adapted to engage with the usual 20 quoin key.

My quoins are used in pairs in the same manner to a certain degree as the old fashioned type, that is to say, as shown in Figs. 1 and 2, I oppose one quoin with another to 25 form a pair, the thick end of one being opposed by the thin end of the other, and the longitudinal rib 6 of each engaging with the longitudinal groove 7 of the other. It also follows, therefore, that the teeth 8 of the one 30 will oppose the teeth of the other, as shown in Fig. 2. If the usual quoin key is inserted so as to engage the teeth of both quoins of a pair in the usual manner, one of the quoins will slide longitudinally with respect to the other 35 and the overall thickness of the pair will be increased because of their tapered shape. To this extent the old and improved new quoins are substantially alike.

However, I achieve a great saving in time 40 by locking my quoins together into trains so that the movement of one will cause a proportionate movement and expansion of all the others in the train. As will be seen from the drawings, I provide at the thin end of my 45 quoin a pin 9 projecting from the tapered face, and in the opposite face of each quoin I form a recess 11 of sufficient depth to receive the narrow end of another quoin. This end is also provided with a hole 12 of such size and 50 so positioned that it will permit of the insertion of the pin 9 of another quoin, thus locking together two quoins which comprise the equivalent halves of two pairs. The other quoins of the pairs are similarly constructed 55 and locked together. As a result, it will be seen that if longitudinal movement is imparted to any one of the quoins of a train by means of the quoin key, it will cause a similar movement of all the other quoins in the train. 60 The train may be made at any desired length. In Fig. 1 a train of four pairs is shown on the left side and a train of three pairs on the lower side. This is only for purposes of illustration, since obviously two 65 trains of two pairs each might have been em-

ployed on the left side and a train of two pairs and a separate single pair might have been used on the lower side. The only limitation as to the number of quoins which may be locked together and operated as a unit are the practical ones of convenience and friction which obviously would increase as the train is lengthened and might conceivably reach such a value that it would be difficult to properly tighten the train by application of the wrench to only a single pair.

In this way I have made it possible to reduce the labor and time element of locking up printing forms very materially without altering the established methods of procedure so seriously as to cause any inconvenience to operatives, who have through long use become familiar with the old fashioned quoins. Furthermore, I make it possible to expand a whole series of quoins at one time and insure an equality of pressure which cannot be obtained where each pair is set up separately and for this reason fewer trips around the form are required than formerly. For the same reason I avoid the very common occurrence of springing the form out of shape midway between its ends which I have already referred to as the result of inadvertently tightening one pair of quoins more than another.

My invention is particularly useful in color printing where it is essential that the body of type be accurately positioned and maintained in that position. The tendency of the old type of quoin to loosen up tends to throw the body of type out of position and it is exceedingly difficult, if not impossible, to bring it back into register by retightening the individual pairs of quoins. With the quoins connected into trains in accordance with my invention the danger of loosening is practically eliminated and, if it should occur, the entire train would be affected to the same extent so that while the actual pressure exerted by the quoins on one side might decrease, it would nevertheless remain uniform. In case retightening becomes necessary all of the quoins will be simultaneously and equally expanded and uniformity of pressure maintained. Thus the tendency to distort or displace the type body is eliminated.

I claim:

A quoin including a wedge shaped body, a pin in the thin end of said body, a hole in the thick end of said body, said pin and said hole being adapted to engage with similar holes and pins respectively in other similar quoins whereby they may be locked together to form a train.

In testimony whereof I have hereunto set my hand on this 8th day of May A. D., 1930.

CHARLES M. DANZIG.
